(57) **CLAIM**

The ornamental design for a elizabethan pet collar, as shown and described.

DESCRIPTION

FIG. 1 is a perspective view of a elizabethan pet collar, showing my new design;

FIG. 2 is another perspective view thereof;

FIG. 3 is a perspective view in open state thereof;

FIG. 4 is a front view thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

In the drawings, the equal-length broken lines depict portions of the elizabethan pet collar that form no part of the claimed design.

1 Claim, 9 Drawing Sheets
